PHONOGRAPH STYLUS

Filed Dec. 27, 1946

INVENTOR.

Lloyd J. Andres

UNITED STATES PATENT OFFICE

2,502,242

PHONOGRAPH STYLS

Lloyd J. Andres, Chicago, Ill., assignor to Permo Incorporated, Chicago, Ill., a corporation of Illinois

Application December 27, 1946, Serial No. 718,751

4 Claims. (Cl. 274—38)

1

This invention relates in general to phonograph styli and more particularly to a new stylus for use in reproducers in which the playing portion is provided with predetermined flexibility and protected against accidental displacement and damage. Phonograph styli previous to this invention, provides with sensitive playing portions, were constructed to protect the playing portion from permanent lateral deformation but no provision made to provide retraction of the playing point to prevent deformation or damage from vertical shock. The present invention not only provides a stylus in which the playing point is in a desirable coaxial alignment with the shank of the stylus but includes provision for both lateral and vertical compliance of the playing point and means for protecting the sensitive playing portion from deformation from shock in both lateral and vertical directions which construction is the principal object of the invention.

A further object of the invention is the provision of means for securing one end of the playing portion in rigid relation with the shank member of the stylus.

Another object of the invention is the provision of a stylus having a playing portion secured therein which portion comprises a freely sprung loop-shaped end terminating in a playing point with said point substantially enclosed and projecting from a cavity in the end of the shank.

These and other objects are described and shown in one embodiment of the invention in which:

Fig. 1 is an enlarged rear elevation of the stylus.

Fig. 2 is a cross-sectional elevation of the stylus shown Fig. 1 taken through section line 2—2.

Fig. 3 is a cross-sectional plan view of the stylus shown Figs. 1 and 2 taken through section line 3—3 Fig. 2.

Fig. 4 is a cross-sectional plan view of the stylus shown Figs. 1 and 2 taken through section line 4—4 Fig. 2.

Referring to Figs. 1 and 2, a substantially cylindrical shank member 1 is provided with a coaxial bore 4 in its central portion in which a playing member 2 is rigidly secured at one end. The remaining end portion of member 2 is formed in a flexible loop 5 projecting outwardly from the shank 1 through a slot 10. The loop 5 ends in an offset terminating in a conventional conical playing point 6 which point is normally positioned substantially in coaxial alignment

2

with the upper end of the playing portion as shown. The slot 10 is flared at its lower portion to form protecting side walls 12—12 as shown. The upper part of the loop 5 of the playing member is rigidly secured by friction in the upper portion of slot 10 for the purpose of positioning loop 5 and the playing point 6 in proper position in the cavity 7. The playing member 2 is prevented from moving longitudinally with respect to the shank by deformations 3 and 9 applied to both shank and playing member as shown Fig. 2. The latter deformation is formed simultaneously with the forming of groove 8 which groove is provided for the registration of a set screw used for securing the shank in a reproducer. Predetermined spacing 11 between the playing member and the side walls 12—12 provides sufficient space for the normal lateral movement of the playing portion without restriction but prevents the playing portion from being laterally sprung beyond its elastic limit.

Referring to Fig. 2, playing point 6 is shown in its normal playing position which provides for predetermined vertical compliance without restriction. When excessive shock in a vertical direction is applied to point 6 by a record or other object, the point and the loop 5 will assume the position shown in dotted lines thus preventing the loop 5 from being sprung beyond its elastic limit by virtue of the record or other object striking the lower end of the shank 1. It is also apparent that the side walls 12—12 will also protect the playing portion from similar shock applied in lateral directions.

Having described my invention, I claim:

1. A phonograph stylus for playing a disc record comprising a shank and a playing member, said shank having its upper end portion 40 adapted to be secured in a reproducer and its lower end portion forming a cavity substantially longitudinal thereof said cavity having an opening also substantially longitudinally located with reference to said shank, said playing member 45 having its upper end coaxially secured in said shank and having a flexible lower end formed in a loop shape projecting outwardly from the axis of said shank and terminating in a playing point, said cavity having a longitudinal slot, 50 said loop extending through said slot said point normally positioned in and projecting from said cavity below said opening and substantially in coaxial alignment with said shank whereby said playing point will retract into said cavity upon 55 application of sufficient vertical pressure to said

shank to move its lower end into contact with said record.

2. A phonograph stylus for playing a disc record comprising a shank and adapted to be secured in a reproducer and having a concentric bore in its central portion and an open cavity of greater diameter than said bore in its lower portion, a slot in said lower portion opening into said cavity, a playing portion having its upper end positioned in said bore including means for securing said upper end in the bore of said shank, said playing portion having a flexible lower end forming a loop projecting outwardly from said shank through said slot, said loop terminating in an offset and an integral playing point, an opening at the lower end of said cavity and said slot extending to said opening with said playing point normally extending below the opening and said point normally positioned substantially coaxial with said shank whereby said playing point and said loop will normally oscillate in both vertical and lateral directions with respect to and independent of said shank when said point engages a record and whereby said playing point will retract into said cavity and the lower end of said shank will move into contact with said record when excessive pressure is applied to said shank.

3. A phonograph stylus for playing a disc record comprising a shank and adapted to be secured in a reproducer and having a concentric bore in its central portion and an open cavity of greater diameter than said bore in its lower portion, a slot in said lower portion opening into said cavity, a playing portion having its upper end portion in said bore, a deformation in said shank and in the upper portion of said playing portion in juxtaposition with each other for securing the upper end portion of said playing portion in rigid relation with said shank, said playing portion having a flexible lower portion forming a loop projecting outwardly from said shank through said slot, said loop terminating in an offset and an integral playing point, an open-

ing at the lower end of said cavity, said opening being coaxial with the upper end portion of said playing portion and said slot extending to said playing portion, said point normally extending below said opening and positioned substantially coaxial with said shank whereby said playing point will retract into said cavity and the lower end of said shank will move into contact with said record when excessive pressure is applied to said shank.

5 4. In a phonograph stylus having a shank and a flexible playing portion secured therein, a cavity in the lower end of said shank, a slot in said lower end of said shank opening into said cavity the upper portion of said slot having a smaller width than the lower portion thereof and forming a pair of upper and lower wall edges substantially parallel to said shank, a looped end of said playing portion extending out of the said upper portion of said slot and embraced by the said upper wall edges and returned into the said lower portion of said slot, in predetermined spaced relation with said lower wall edges, said looped end terminating in a playing point, an opening in the lower end of said cavity, said slot extending to said opening said playing point normally extending below said opening and in a substantial line with said shank and projecting from the lower end of said shank.
